UNITED STATES PATENT OFFICE.

MOSES L. BULSON, OF GLASCO, KANSAS.

OIL-BURNER.

1,014,999.

Specification of Letters Patent. Patented Jan. 16, 1912.

Application filed April 18, 1911. Serial No. 621,930.

To all whom it may concern:

Be it known that I, MOSES L. BULSON, citizen of the United States, residing at Glasco, in the county of Cloud and State of Kansas, have invented certain new and useful Improvements in Oil-Burners, of which the following is a specification.

My invention relates to burners for burning hydrocarbon, such as crude oil, kerosene, 10 gasoline, etc., and the object of the invention is to provide a very simple, durable and effective burner of this character particularly adapted for use with cooking or heating stoves, and so arranged that it may be 15 easily put in place within an ordinary stove without materially changing the stove or furnace to which it is applied.

A further object is to provide a burner of such simplicity that the parts cannot get out 20 of order and so constructed that the burner may be readily cleaned whenever desired.

With these and other objects in view, as will more fully appear as the description proceeds, the invention consists of certain 25 constructions, arrangements and combinations of the parts that I shall hereinafter fully describe and claim.

For a full understanding of the invention, reference is to be had to the following description and accompanying drawing, in which:

Figure 1 is a sectional view of a stove with my improved burner in place therein, the burner being in section on a plane 35 passing through the air chambers; Fig. 2 is a transverse section of the burner, the section line extending between the air chambers; Fig. 3 is a horizontal section through the cap 10 above the nozzle section 9. Fig. 4 is a perspective view of the base 40 of the burner. Fig. 5 is a perspective view of the nozzle cap. Fig. 6 is a perspective view of the cover.

Corresponding and like parts are referred 45 to in the following description and indicated in all the views of the accompanying drawings by the same reference characters.

Referring to the drawings, 2 designates a base having the form of a pan with an up- 50 standing marginal rim 3 from which projects the annular flange 4. If the burner is intended to be used in a circular stove, as for instance in an ordinary heating stove, the diameter of the base 2 including the flange 4

is about equal to the internal diameter of 5 the stove and the base 2 rests upon the grate bars thereof.

The base 2 is formed with a central gas generating chamber 5 the walls of this chamber being preferably cast integral with 60 the base. The base immediately beneath the chamber 5 is formed with the perforation 6 into which passes a supply pipe 7, and the upper wall of the chamber 5 is perforated and screw-threaded for the reception of a 65 nozzle 8. This nozzle is formed with a tip 9 which is removable so that the tip may be replaced when necessary. The upper end of the tip is formed with radiating notches 9a. A removable cap 10 rests upon the upper 70 end of the tip, this cap being provided with radiating spaced lugs 11 so as to center the cap upon the tip and permit the gas from the nozzle to pass downwardly between the nozzle and the downwardly extending margin 75 of the cap 10, the flames from the burning gas being directed against the walls of the generating chamber 5.

Located at intervals around the generating chamber 5 and preferably between the generating chamber and the upstanding rim 3, are the air chamber sections 12, these chamber sections being preferably cast in one piece with the base 2. These chamber sections are elliptical in cross section and open on the 80 under side of the base by the elongated opening 13. The upper end of each chamber section is constructed so as to provide an upwardly extending nipple 14, this nipple being elliptical in plan and formed with 85 the elliptical opening 15. These air chamber sections 12 extend upwardly to a height somewhat above the gas generating chamber 5.

Extending over the nozzle 8 and the generating chamber is a cover 16 which is made of a relatively heavy casting, this cover being approximately circular in form and being somewhat larger in internal diameter than the external diameter of the gas generating chamber 5. Formed integral with the cover are the elliptical air chamber sections 17 which are designed to fit upon and form continuations of the air chamber sections 12, the lower edges of the chamber sections 17 fitting down upon the shoulders surrounding the nipples 14. It will be seen that this cover is therefore supported upon

the upper ends of the chamber sections 12. The chamber sections 17 have outlet openings 18 on their inner walls, these outlet openings being all directed toward the nozzle 8. It is to be noted that the lower edge of the concavo-convex cover 16 is supported above the upper edge of the upstanding wall 3 so that the flames, downwardly directed by the cover, which acts as a flame deflector, are forced downward beneath the lower edge of the cover and then outward between and around the air chambers. In order to permit the cover to be readily removed it is provided with a lug 19 upon its upper face. 15 Normally however, the cover remains solidly in place upon the burner, the cover having such weight that it is not readily removed.

The operation of my invention will be obvious from what has gone before. Oil is permitted to flow into the generating chamber 5, and the heat of the flames directed downward upon the generating chamber by the inverted cap 8 causes the oil within the chamber 5 to vaporize, the vapor passing up from the nozzle and being ignited. As it passes from the cap, the flames are directed downward and outward by the rounded outer face of the generating chamber and by the concavo-convex cover 16 and pass downward between the cover and the generating chamber and then upward and outward between the air chambers 12, thus thoroughly heating the air in the air chambers. Thus the air which is directed toward the nozzle and the vapor which passes out of the nozzle are both thoroughly heated and put in the best condition for combination. When the burner is first started sufficient oil is poured into the pan formed by the base 2 and the oil is ignited. The oil in the pipe 7 is then allowed to flow into the chamber 5 and the ignited oil in the pan surrounding the chamber 5 heats the chamber sufficiently to start vaporization. After that the burner takes care of itself.

I have found in practice that a burner of this character gives out a very large degree of heat with a relatively small consumption of fuel. It has no complicated or delicate parts and hence can stand rough usage much better than ordinary oil burners. The large amount of relatively thick metal exposed to the heat acts to vaporize the oil very quickly and prevents this vaporization from ceasing with slight fluctuations in the oil supply. By removing the cover the upper face of the base may be readily cleaned or the tip removed and reapplied. There is very little chance for the lodgment of soot, and if the parts do become coated with soot, the soot may be easily removed and this without the necessity of taking the burner out of the stove, furnace or heater to which it is applied.

What I claim is:

1. An oil burner including a base having the form of a pan, a gas generating chamber forming part of the base, a supply pipe opening into the gas generating chamber, a nozzle projecting from the chamber opposite to the supply pipe, a plurality of air chambers located around the generating chamber and having discharge openings, said air chambers opening upon the under side of the base, and a deflecting cover extending over the nozzle and supported upon the base and acting to direct the air from said air discharge openings toward the nozzle. 70 75

2. An oil burner including a base having the form of a pan, a gas generating chamber formed within the base, a fuel supply pipe opening into the gas generating chamber, an upwardly projecting nozzle extending from the chamber, a cap resting upon the upper end of the nozzle and deflecting the vapor therefrom downward against the base, a plurality of air chambers mounted on the base and located at intervals around the gas chamber, each air chamber being formed with an outlet opening and a cover supported upon the base and extending over the gas generating chamber and inclosing the nozzle thereof, said cover acting to direct the air entering through the outlet openings of the air chambers toward the nozzle. 80 85 90 95

3. An oil burner including a base having the form of a pan, a gas generating chamber integral with the base and formed in the center thereof, a fuel supply pipe opening into the generating chamber, an upwardly projecting nozzle extending from the gas generating chamber, a deflecting cap on the nozzle, a plurality of air chambers formed integral with the base and located at intervals around the gas chamber, each of said air chambers being open at its lower end, and a concavo-convex cover larger in diameter than the diameter of the generating chamber, said cover being provided at intervals with chamber sections completing the chamber sections carried upon the base, each of said chamber sections in the cover being provided with an inwardly directed opening. 100 105 110 115

4. An oil burner including a circular pan-shaped base having an annular marginal flange, a central gas generating chamber formed integral with the base and having a rounded upper wall, a nozzle projecting from the gas generating chamber and having a removable tip, a concavo-convex deflecting cap supported on the end of the nozzle, air chamber sections integral with the base and located at intervals around the gas generating chamber, said air chamber sections being open at their lower ends and at their upper ends, a concavo-convex cover less in diameter than the diameter of the pan-shaped portion of the base and having a plu- 120 125 130

rality of air chamber sections formed integral therewith and resting upon the air chamber sections first-named, said last-named air chamber sections being formed with openings directed toward the nozzle, and a supply pipe opening into the generating chamber.

In testimony whereof, I affix my signature in presence of two witnesses.
